ALEXANDER MEISSNER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY

ARRANGEMENT FOR TRANSMITTING AND RECEIVING SHORT WAVES

Application filed April 6, 1927, Serial No. 181,462, and in Germany April 8, 1926.

This invention relates to an arrangement in wireless communication for transmitting and receiving short waves. More particularly the invention relates to an arrangement 5 whereby directional radiation is obtained from a plurality of antennæ inclined to the horizontal and provided with reflecting shields.

Experiments have shown that the working 10 with horizontal polarization, i. e., the use of electrical fields parallel to the surface of the earth is more suitable for antenna systems for space radiation than the normal vertical antenna, indeed, the most favorable plan is to 15 upwardly radiate the radiation approximately at an angle of from 60 to 80 degrees. A very suitable form of antenna for such directional radiation is to use a plurality of horizontal antenna which are jointly excited, 20 but are separated by more than $\frac{1}{4}$ wave-length. With such a system there is obtained a perfectly directional radiation, so that by means of such a radiation the lowest losses incidental to the propagation of the radiations 25 through the atmosphere are insured.

It is a good plan to mount the aerial not perfectly horizontal, but rather with a small angle with relation to the horizon in order to impart a definite angle to the radiations. 30 Such a horizontal antenna, of course, radiates in upward direction and in downward direction in the same manner. In order that the loss radiation entering the ground may be diminished, the antenna is either suspended 35 at $\frac{1}{4}$ wave-length from the ground, with the latter acting as a reflector, or else the reflector action of the ground is improved by metal surfaces or a wire system provided between antenna and the ground. It is a suitable 40 plan to tune these wires to the transmission wave in order to perfect the reflector action. The entire system proves very suitable both for sending as well as for reception work.

45 For energy supply either from the transmitter or to the receiver apparatus, coils are inserted in the horizontal plane to which the energy line is coupled. The energy lines for the various antenna must all be of the same length for the reason that all antennæ must

here oscillate at the same phase. It is suitable to effect this in such a manner that from the transmitter only one energy line is brought which, at two points, is branched into equally long lines as shown in Fig. 1. 55

For a more complete understanding of the invention, reference is made to the accompanying drawings, in which Fig. 1 is a dia- 60 grammatic representation of an equal length lead-system for supplying energy to a plu- 65 rality of antennæ; Fig. 2 shows the inclina- 70 tion of the antenna to the ground; and Fig. 3 shows how a reflecting screen is used with each antenna.

As shown in Fig. 1, the energy leads from 65 the transmitter 1 to each of the antennæ 2, are all of the same length and as a result all the antennæ oscillate at the same phase.

The antennæ are arranged in a direction transverse to the direction of desired propa- 70 gation and in a plane which forms an angle of inclination of less than 40 degrees with the surface of the earth. Fig. 2 clearly shows the inclination. By means of this angle of in- 75 clination the energy waves are radiated upwardly in a broadside manner to the heavy side layer from which they are reflected back to the earth's surface.

In order to diminish the energy loss due to the radiations entering the ground the 80 antennæ are suspended at $\frac{1}{4}$ wave length from the ground, whereby the ground acts as a reflecting surface, or a reflector in the form of a metal surface or wire system is used with the antennæ as shown at 3 in Fig. 85 3. When a wire system is used as a reflector, the wires are preferably tuned to the transmission wave to perfect the reflector action.

Having thus described my invention, what 90 I claim is:

1. In directional transmission of radio sig- 95 nals the combination of a transmitting appa- ratus, a plurality of antennæ arranged in a plane having an angle of inclination less than 40 degrees and greater than zero degrees with reference to the horizontal, said antennæ being parallel to each other and over $\frac{1}{4}$ wave length apart, and equally long energy leads for transferring energy from said transmit- 100

ting apparatus to said antennæ whereby said antennæ are excited to oscillate in the same phase and whereby the propagation will be of a broadside nature and in a direction at 5 right angles to the plane of said antennæ.

2. The combination as claimed in claim 1, in which means are employed for reflecting those radiations which are directed toward the earth, in a manner so that they combine 10 with and strengthen the radiations directed away from the ground.

3. The combination as claimed in claim 1, in which a metal shield is arranged under each antenna whereby the radiations which 15 are directed toward the ground are reflected upwardly.

4. The method of directional signaling which consists in arranging a plurality of antennæ in a plane having an angle of inclination less than 40 degrees and greater than zero degrees with reference to the horizontal, energizing said antennæ in a manner 20 to cause them to oscillate at the same phase, and reflecting the radiations which would normally be absorbed by the ground to combine with and strengthen the radiations directed away from the ground.

5. The method of directional signaling which consists in arranging a plurality of 30 antennæ in a plane having an angle of inclination less than 40 degrees and greater than zero degrees with reference to the horizontal and energizing said antennæ in a manner to cause them to oscillate at the same phase 35 to produce a broadside radiation in a direction at right angles to the said plane of said antennæ.

6. In combination, a plurality of individual antennæ arranged in a plane, a source of 40 high frequency energy, and a plurality of equal length leads between said source and said antennæ, the plane of said antennæ being inclined with reference to the horizontal so as to form an angle between 40 degrees 45 and zero degrees to form the desired angle with the ground for directional broadcasting.

7. In combination, a plurality of antennæ arranged parallel to each other and inclined at a desired angle to the ground greater than 50 zero degrees, a source of high frequency energy and a plurality of equal length leads from said source to said antennæ whereby said antennæ are energized in phase for directional broadcasting.
